UNITED STATES PATENT OFFICE.

PATRICK T. MC LAUGHLIN AND WILLIAM ANDERSON, OF MIAMI, OKLAHOMA.

BOTTLE-EXCHANGE RECEPTACLE FOR CONTAINING MILK BOTTLES.

Application filed January 9, 1926. Serial No. 80,283.

This invention relates to a bottle exchange receptacle for containing milk bottles or the like.

An important object of the invention is to provide a device of this character adapted to contain a milk bottle either full or empty and of such structure that the removal of the contained bottle is readily accomplished by the insertion of a second bottle to thereby substantially insure the substitution of an empty bottle for a full one or a full bottle for an empty one.

A still further object of the invention is to provide a device of this character having means for housing the contained bottle so as to protect the same against the attacks of flies and other insects and to hide the same from the view of mischievous boys or tramps who otherwise might remove the same.

20 A further object of the invention is to provide a device of this character which may be very readily and cheaply constructed and which will be durable and efficient in service.

25 These and other objects we attain by the construction shown in the accompanying drawings, wherein for the purpose of illustration is shown a preferred embodiment of our invention and wherein:-

30 Figure 1 is a side elevation of a bottle exchange receptacle constructed in accordance with our invention;

Figure 2 is an enlarged vertical sectional view therethrough;

35 Figure 3 is a section on the line 3—3 of Figure 2;

Figure 4 is an enlarged detail view showing the construction of one of the retaining elements.

40 Referring now more particularly to the drawings, the device includes an open bottomed tube 10 having at vertically spaced points brackets 11 whereby it may be secured to a suitable support, such as the wall

45 of a building. The upper end of the tube is preferably beveled and is provided with a cover 12 hinged, as at 13, and of sufficient size to insure against entry to the upper end of the tube of snow or sleet which would collect upon the contained bottle and render the removal thereof difficult.

Within the tube at vertically spaced points are arranged retaining elements 14 in the form of upwardly converging spring fingers

50 55 15 through which a bottle may be inserted from the lower end but from which a bottle

once inserted may not be removed except by elevation thereof. The lower set of spring fingers 15 is arranged immediately above the bottom of the tube while the second or upper set is arranged so that the upper ends of the fingers are spaced from the upper end of the tube a distance slightly less than the height of the bottle which is to be accommodated. The space between the upper and lower sets is preferably of sufficient size to accommodate a bottle, the lower end of which rests upon the fingers of the lower set.

The spring fingers are preferably produced by employing a single strip of resilient wire which, intermediate its ends, is bent to form a plurality of loops 16 projecting to one side of the wire. The wire is then bent in the form of a circle and sprung into a pressed groove 17 formed in the interior wall of the casing. It will, of course, be understood that this is merely a preferred method of forming the retaining element 14 and that other means may be employed where this is found desirable. The wall of the casing between the upper and lower retaining elements 14 is preferably provided with a sight opening 18 so that it may be noted whether there is contained within the casing a bottle which is to be removed.

In the use of the device, assuming a full bottle to be in position within the tube and with its lower end resting upon the fingers 14, the housewife, in order to secure the same, inserts a second and empty bottle in the lower end of the tube so that it engages the lower end of the contained full bottle, forcing the full bottle upwardly until it engages the lid 13 and raises the same. At this time, the empty bottle will be arranged with its bottom above the upper ends of the fingers of the lower retaining element 14 and is accordingly unremovable. The full bottle may be reached through the top of the container and is removed. The milk-man, on his rounds, reverses the operation, inserting a full bottle and removing the empty bottle. It will, of course, be understood that the cover 12 may be provided with a lock, as indicated at 18', if so desired, in which event removal of the contained bottle will be substantially impossible except by authorized persons.

Since the construction hereinbefore set forth is obviously capable of a certain range of change and modification without mate-

rially departing from the spirit of the invention, we do not limit ourselves to such specific structure except as hereinafter claimed.

5. We claim:—

A bottle exchange comprising a tubular casing open at its opposite ends and provided at its inner surface and at a point between its ends with an annular depression, 10 a bottle retaining element consisting of a re-

silient wire having sections folded upon each other forming fingers, said fingers being inwardly inclined toward each other and the material of the wire lying between the fingers being arcuately curved to fit in said 15 groove.

In testimony whereof we hereunto affix our signatures.

PATRICK T. McLAUGHLIN.
WILLIAM ANDERSON.
